UNITED STATES PATENT OFFICE.

CORTLAND W. DAVIS AND VICTOR S. JOHNSON, OF CHICAGO, ILLINOIS, ASSIGNEES TO THE MANTLE LAMP COMPANY OF AMERICA, OF CHICAGO, ILLINOIS, A CORPORATION OF ILLINOIS.

HYDROCARBON-BURNER.

1,256,879.

Specification of Letters Patent. Patented Feb. 19, 1918.

Application filed August 28, 1914. Serial No. 859,073.

To all whom it may concern:

Be it known that we, CORTLAND W. DAVIS and VICTOR S. JOHNSON, citizens of the United States, residing at Chicago, in the county of Cook and State of Illinois, have invented certain new and useful Improvements in Hydrocarbon - Burners; and we do hereby declare the following to be a full, clear, and exact description of the invention, such as will enable others skilled in the art to which it appertains to make and use the same.

This invention is a hydro-carbon burner of the blue flame wick type adapted for the production of heat or light.

In burners of this classification, it has been observed that parts of the burner adjacent the flame absorb heat from the flame and transmit the same to their supporting elements thereby causing the burner structure to become excessively heated. This unrestricted heat transmission results in what is known as "creeping up of the flame."

In blue flame burners, and especially those adapted for use in connection with incandescent mantle lamps, the "creeping up" defect has been found of considerable annoyance. This defect renders it very difficult to position the wick properly. Not infrequently an operator will set the wick a little too high whereby after the fuel increases, due to "creeping up," the flame is beyond the capacity of the burner, resulting in imperfect combustion and depositing of carbon deposits on the mantle.

An object of this invention is to overcome the defects above stated and to insulate parts of the burner from their supporting elements, thereby restricting heat from disseminating throughout the burner structure, and especially to segregate or insulate the parts adjacent to the flame from their supporting elements, thereby increasing the efficiency of the burner by reducing the "creeping up" of the flame.

It is an aim of the invention, also, to retain the heat in the parts of the burner adjacent the flame, thereby restricting the carbon crust from forming on these parts and interfering with the air introduction to the flame, while at the same time assisting combustion by helping keep the fuel in a hot vaporized condition.

A further purpose of the invention is to simplify the construction of a burner, in-

volving heat controlling features whereby the parts may be easily manufactured and readily assembled.

While the accompanying drawings disclose several embodiments of the invention, the disclosures therein made are to be understood as illustrative only, and not as defining the limits of the invention.

In the drawings:

Figure 1 is a vertical sectional view disclosing certain parts of the burner, adjacent the flame, insulated from other parts thereof.

Fig. 2 is a detail, partial sectional view disclosing means of insulating the gallery sections.

Fig. 3 discloses a ring of heat resisting material interposed between the base and gallery.

Fig. 4 discloses another means of interposing heat resisting material between the gallery sections.

Fig. 5 discloses the flame protecting flange separated from the wick tube by heat resisting material retained between the two parts.

Fig. 6 is another means of interposing heat resisting material between the protecting flange and the wick tube.

Fig. 7 is a detail sectional view of a collar of heat-resisting material.

The invention contemplates the production of a burner for heating or illuminating purposes wherein the parts adjacent the flame are segregated from other parts to retain the heat imparted thereto by the flame, instead of permitting the heat to be disseminated to other parts of the burner where it will be instrumental in producing undesirable results, such as over production of fuel and creeping up of the flame. It is proposed to interpose heat-resisting material between the spreader and the inner wick tube, between the flame protecting flange and the outer wick tube, between the gallery, or parts thereof and the base of the lamp between parts of the burner base, or any combination of such insulating means as will produce the desired result. By so doing, the heat will be retained in those parts nearest the flame to assist in the combustion of fuel, while the parts of the burner which will affect the wick, other than at the burning point, will be maintained in a comparatively cool condition.

By "insulating" parts of the burner from

other parts thereof, we refer to any means recognized as a non-conductor of heat or to material which will resist the transmission of heat.

- 5 In the embodiment of the invention disclosed in Fig. 1, the burner is shown as comprising a basket base 1 and a plurality of members 4, 7 and 8. The lower or basket member 1 is preferably perforated as shown
10 at 2 to leave narrow bridges of metal to assist in the dissemination of any heat which may be conducted to the base from the flame before the heat can be transmitted to that portion of the base which contacts with the
15 fuel supply. The base may be provided with suitable means to secure it to a reservoir. The member 4 is designed to be clenched or otherwise suitably secured to the base 1. Lower member 1 is shown provided with a
20 rib 3, around which a depending flange 6 of the member 4 may be bent to retain a suitable heat resisting material, such as a ring of asbestos, between the members 1 and 4 and to maintain these parts out of metallic contact.
25 The gallery of Fig. 1, is shown provided with the plurality of sections above described. Upon the section 7 which may be imperforate, is mounted the cone cap section 8. On the section 7 may also be mounted
30 the usual chimney band 9. The lower end of the section 7 is shown provided with a resilient depending flange 7^a designed to engage the flange 5 of the section 4, to maintain the gallery in position on the base.
35 In Fig. 2 the burner is shown provided with the cone cap section 8, the section 7, and a section 44, the section 7 being positioned intermediate sections 8 and 44. In this construction, the section 7 is shown provided with a bifurcated flange portion 10, 11, to receive a flange 12 of the cone cap 8. Between said flanges 10, 11, 12 is positioned suitable insulating, or heat resisting, material indicated at 13. This material may be
40 in the form of asbestos which is clamped between said parts, and in this figure the cone cap is shown fixed to the gallery. Suitable insulating, or heat resisting, material 13 is shown employed between the intermediate
45 section 7 and the section 44. This heat resisting material is shown clamped between the retaining flange 14 and an annular rib 15. In this construction the entire gallery section is removable from the base 1, the
50 section 44 of the gallery being secured to the section 7, and provided with the retaining flange 17 to engage the supporting portion 18 of the base 1.
55 In Fig. 3, the base 1 is shown provided with an annular seat 19 on which is positioned a ring of heat resisting material 20, which may be of lava, magnesium or the like, said ring being provided with a recess indicated at 21 to receive studs 22 formed
60 on the flange 23 of the section 7 of the gal-
65

lery. This ring 20 is preferably retained in position on the base 1, by the flange 24, although any other suitable retaining means may be employed. In this construction the cone cap 8 is removably mounted upon the section 7 as in Fig. 1. In this construction of the burner, heat from the flame will be retained in the sections 7 and 8, but restricted from traveling to the burner base 1 by the insulator 20.

75 In Fig. 4 the gallery is shown as having the cone cap 8 removably mounted upon the section 7, said section being shown insulated from the section 44 by a suitable non-conductor of heat indicated at 13. This non-conductor 13 may be retained between the parts 7 and 44 by the flange 14 co-operating with the annular rib 15. The gallery 9 is supported from the base 1 in any desired manner, and in this view is shown provided with a resilient flange 17 similar to that shown in Fig. 2.

80 The usual wick tube 25 and inner wick tube 26, is provided for the burner. The outer wick tube may be mounted in a suitable manner from the base 1, while the inner wick tube may be of the central draft type and extend from the base of the reservoir. The outer wick tube 25 is shown provided with a flame protecting flange, and in Fig. 5 this flange is indicated at 27. It is proposed to mount the flange upon the outer wick tube 25 in a suitable manner, but out of metallic contact therewith. In Fig. 5 this flange 27 is provided with a depending 90 collar 28. This collar is maintained out of metallic contact with the outer wick tube 25 by suitable heat resisting means 29 interposed between the members 25, 28. This heat resisting material 29 may be in the form of asbestos rings, which is shown between the crimped portions 30, of collar 28, and the tube retaining means 31. The upper end of the flame protecting flange may be brought into contact with the wick above 100 the end of the outer wick tube, but out of contact with said tube. In this construction the heat is retained in the flame protecting flange, which prevents a deposit of carbon crust thereon, besides assisting in the vaporization of the oil. The heat resisting material 29 serves to prevent the heat from the collar 28 being conducted down the wick tube 25.

105 In Fig. 6, the flame protecting flange 27 is shown extended across in contact with the wick 32, but out of contact with the outer wick tube 25. This embodiment of the flame protecting flange also contemplates the provision of the depending collar 28 and a 110 collar of heat resisting material 33, interposed between the depending collar 28 and the upper end of the outer tube 25. This heat resisting material 33 may be lava, magnesium, or any other suitable material and 115

is shown provided with a retaining portion 34 at the upper end thereof, which may rest upon the upper end of the outer wick tube 25. The lower end of this collar 33 may be seated upon suitable means, such as an annular retaining rib 35 on the outer wick tube 25, and if found desirable, the insulating ring 33 may be cemented to the wick tube 25 and to the depending collar 28 by 10 a suitable heat resisting cement.

In Fig. 1, the inner wick tube 26 is shown provided with a supporting device, such as an annular rib 37, which serves as a seat for a collar or heat resisting material, indicated 15 at 38. This material may be similar to that shown at 33, in Figs. 6 and 7 and is interposed between the inner wick tube 26 and the flame spreader 39, of any preferred construction. The function of this spacing element 20 38 is to retain the heat within the flame spreader 39, thereby promoting combustion at a point at the upper end of the wick, and also preventing the heat, from the spreader, from being disseminated through 25 the inner wick tube to parts where it is not desired in the burner. In Fig. 1 the spreader is shown provided with a contracted lower imperforate portion 40 and an upper perforate portion 41 to permit air from the 30 inner wick tube to flow through the sides of the spreader to the flame. This spreader is provided also, with a conical portion 42 which may be provided with a row of perforations to admit air from the inner wick 35 tube to the upper part of a flame when the wick is turned to its maximum height. It is preferred to make the top plate 43 of the spreader imperforate.

While many other changes and modifications might be disclosed, not only in the gallery and base portions, but, also, in the outer wick portion and the spreader portion, the right is reserved to make such changes and alterations as will insulate a part of a 45 burner adjacent the flame, from other parts of the burner which it is not desired to heat, as fairly fall within the scope of the appended claims, thereby maintaining the heat in those portions where they will serve 50 to promote combustion and prevent deposit of unconsumed matter.

Having thus described our invention, what we claim as new and desire to secure by Letters Patent is:

55 1. A burner comprising a plurality of parts including a basket base, a cone structure mounted above said basket base, and a non-heat conductor disposed between the cone structure and the basket base to restrict 60 the transmission of heat from the cone structure to the base.

2. In a burner, a foraminous base and a gallery comprising a flame section, an intermediate section, and a base engaging section, and heat resisting means between the

flame section and the intermediate section, and between the intermediate section and the base engaging section.

3. A burner including a foraminous base section, a cone structure supported above 70 the base section, and a fixedly mounted ring of heat resisting material disposed between said parts.

4. In a burner, a wick tube, a flame protecting flange supported thereby near the 75 upper end of the tube, and heat resisting material interposed between the flange and wick tube.

5. In a burner, a wick tube, a flame protecting flange, heat resisting material to 80 maintain said flange out of contact with said wick tube, and means to retain said heat resisting material in position.

6. A burner comprising outer and inner wick tubes, a flame protecting flange mounted 85 near the upper end of the outer wick tube, a thimble type flame spreader mounted from the inner wick tube, a ring of heat resisting material fitted between the body of the flame spreader and the wick tube to separate the flame spreader out of contact with the wick tube, and another ring of heat resisting material interposed between the flame protecting flange and the wick tube to support the flange out of contact with the 95 wick tube.

7. In a burner, the combination with a base, a gallery removably mounted from the base and composed of a plurality of sections, the sections of the gallery being supported 100 out of metallic contact by heat resisting material; inner and outer wick tubes, a flame protecting flange mounted out of metallic contact with the outer wick tube by heat resisting material, a flame spreader, and heat 105 resisting material supporting the flame spreader and maintaining the same out of metallic contact with the inner wick tube, whereby the heat generated by the flame may be retained in the parts of the burner 110 adjacent the flame and the conduction of heat to the lower parts of the burner from a plurality of sources prevented.

8. A gallery for a burner comprising a plurality of members including a lower 115 member having a rib, a burner cone member, an intermediate section of an upper gallery member having a bifurcated retaining flange at the interior portion and a re-entrant flange at the exterior portion, a 120 flange of the burner cone member extending between the bifurcated flange portions, and heat resisting material interposed between the flange of the burner cone member and the bifurcated retaining flange portions, 125 and also around the rib between the retaining flange of the upper gallery member and the lower gallery member.

9. A burner comprising a plurality of members including a base member and a 130

- gallery member adapted to be removably mounted on the base member by a retaining flange, and heat resisting material interposed between the flange and the remaining portion of the gallery member to be removed with the gallery member, said heat resisting material serving to restrict the conduction of heat from the gallery member to the base member.
- 10 10. In a burner, a wick tube, a flame spreader having a substantially imperforate top and a perforated cylindrical section, said cylindrical section having a contracted lower end, and a tubular member of heat resisting material to support the spreader out of contact with the wick tube.
11. A burner comprising a burner base, a cone cap structure having an upper member and a lower member, insulating means positioned between the members to maintain them out of metallic contact, a wick tube mounted from the base, said wick tube being provided with a flame protecting flange, and insulating means to maintain the flame protecting flange out of metallic contact with the wick tube, whereby heat from the flame may be dissipated before being conducted to the burner base and the lower part of the wick tube.
- 20 12. A burner comprising a base, a burner gallery of a plurality of members, means to secure the gallery to the base, and insulating means secured between the members of the burner gallery.
- 30 13. A burner comprising an inner wick tube provided with an annular rib, a collar of heat resisting material mounted on the rib of the inner wick tube, and a flame spreader removably mounted on the wick tube and maintained out of direct contact therewith by the collar of heat resisting material.
- 40 14. A burner comprising an inner wick tube provided with an annular rib, a collar of heat resisting material provided with an annular flange adapted to rest upon the wick tube and a flame spreader removably mounted on the collar of heat resisting material, said flame spreader resting upon the annular flange of said collar.
- 50 15. A burner having a wick tube, a flame protecting flange mounted at the top of the wick tube, and heat resisting material interposed between the flame member and the wick tube to maintain them out of metallic contact with each other.
16. A burner having a wick tube, a flame protecting flange mounted at the top of the wick tube, and a collar of heat resisting material having an annular flange to rest upon an end of the wick tube, said collar maintaining the flame member and wick tube out of contact with each other, the flame member having means to support the same on the wick tube from the collar. 60
17. A burner having an inner wick tube provided with supporting means near its upper end, a collar of insulating material adapted to rest upon said supporting means and a flame spreader having a foraminous side wall, provided with a shoulder above the upper end of the collar, whereby the spreader may be mounted on the collar of insulating material out of direct contact with the wick tube. 70
18. In a burner, an inner wick tube provided with an annular flange near its upper end, a collar of insulating material having an inwardly directed flange at one end, and a flame spreader having a foraminous side wall, the lower part of which is of lesser diameter than the remaining part of said wall, to provide a shoulder which is adapted to contact with the upper end of the collar, the lower end of the spreader resting upon the flange of the collar to thereby mount the spreader out of contact with the parts of the burner other than the collar of insulating material. 75
19. A burner of the blue flame type, having in combination means for supplying volatile fuel to the flame, a flame spreader thermally isolated from said means, a flame cone cap and sustaining and heat insulating means for said cap supported on a part of the burner. 90
20. A burner of the blue flame type, having in combination means for supplying volatile fuel to the flame, a flame spreader thermally isolated from said means, a flame protecting flange also thermally isolated from said means, a flame cone cap and sustaining and heat insulating means for said cap supported on a part of the burner. 100
